DENTAL FLOSS HOLDER

Thomas P. Centofanti, 15631 Fairfield,
Livonia, Mich. 48154

Filed Mar. 6, 1970, Ser. No. 21,764

Term of patent 7 years

Int. Cl. D24—03; D4—02

U.S. Cl. D24—1

FIG-1

FIG-6

FIG. 1 is a perspective view of a dental floss holder showing my new design;

FIG. 2 is a view of the top side, the bottom side being a mirror image of the top side;

FIG. 3 is an end view looking from the left of FIG. 2;

FIG. 4 is an end view looking from the right of FIG. 2;

FIG. 5 is an enlarged, fragmentary view of one of the arms; and

FIG. 6 is a perspective view of a modified embodiment of the dental floss holder in combination with a toothbrush.

I claim:

The ornamental design for a dental floss holder, as shown and described.
